MOLDED ELECTRIC CORD CONNECTOR

Masami Seidoh, Tokyo, Japan, assignor to Honeywell Inc.,
Minneapolis, Minn., a corporation of Delaware

Filed Sept. 21, 1964, Ser. No. 81,807

Term of patent 14 years

(Cl. D26—1)

FIG. 1

FIG. 2

FIG. 3

FIG. 4

FIG. 1 is a rear elevational view of a molded electric cord connector showing my new design;

FIG. 2 is a side elevation view thereof;

FIG. 3 is a front elevational view thereof; and

FIG. 4 is a top plan view thereof.

The fragmentary broken-line showing of a power cord is for illustrative purposes only.

I claim:

The ornamental design for a molded electric cord connector, substantially as shown and described.
